VALVE

William E. Sloan, River Forest, Ill., assignor to
 Sloan Valve Company, Chicago, Ill., a corpora-
 tion of Illinois

Application February 26, 1940, Serial No. 320,789

6 Claims. (Cl. 137—111)

This invention relates to valves, but is concerned more particularly with valves which are capable of quietly throttling a flow and of shutting off the flow entirely. The general object of the invention is the production of a new and improved combined quiet-throttling and shut-off valve, termed a control valve, adapted particularly for use in connection with a direct-connected flush valve.

A specific object of the invention is the provision of an angle-pattern valve of the above character arranged with a side inlet and an end outlet, whereby the length of the valve may be increased as much as needed without affecting the distance which the valve extends away from a finished-wall surface through which the supply pipe connected with the inlet of the valve extends.

Another specific object is the production of a new and improved valve-operating arrangement which is not subject to longitudinal movement giving rise to undue wear and to clicks or other noises, incident to the opening and closing of the associated flush valve.

Another object is the provision of suitable means for supporting and guiding the valve and throttle mechanism so that it is accurately centralized in its highly throttled positions.

Another object is to provide the control valve with a readily renewable throttle, and to provide for the self-centering of the throttle when it is replaced or renewed.

Another object is to provide a new and improved cushion assembly for receiving the impact of the high-velocity jets emerging from the restricted throttling throat and quietly diverting them into a slowly moving stream.

Still another object is to provide a control valve which is readily adjustable to any desired throttling position and in which the throttle proper is protected from direct jet impact on the initial opening movement of the valve, and in which a pocket is provided to catch and hold temporarily any foreign material, such as white lead, until the throttle opening is sufficient to allow it to wash through.

The foregoing and other objects and features of the invention will become more apparent as the description progresses.

GENERAL DESCRIPTION

Referring now to the accompanying drawing, comprising Figures 1 to 9, they show sufficient views of an installation including one embodiment

ment of the invention to enable the invention to be understood.

Figure 1 is a top sectional view showing the preferred embodiment of the new and improved 5 shut-off and throttle valve shown, for convenience, in the position it assumes when rotated ninety degrees in a counter-clockwise direction from the installed position illustrated at 1 in Figure 4;

10 Figure 2 is a similar view, partly in section, showing the device adjusted to throttle the flow from a comparatively high-pressure supply line;

15 Figure 3 is a further similar view, partly in section, showing the device adjusted to its full-open position to pass the required rate of flow when installed in a location where the supply pressure is comparatively low;

20 Figure 4 shows a top view of the device when installed adjacent a finished wall surface and in association with a direct-connected flush valve;

25 Figure 5 shows a front view of the equipment illustrated in Figure 4;

Figure 6 is an enlarged top view of the throttle proper when removed from the valve device;

30 Figure 7 is a quarter-section front view of the throttle;

Figure 8 is an enlarged top view of the cushion assembly 24 when removed from the valve casting;

35 Figure 9 is a quarter-section front view of the cushion assembly.

DETAILED DESCRIPTION

A detailed description of the illustrated apparatus will now be given.

The installation

Referring now particularly to Figures 4 and 5, the inlet 2 of the combined throttle and shut-off valve 1 is connected to the outer end of supply pipe 48, extending out through wall 49. The outlet 3 of valve 1 is connected through nipple 28 to the inlet of flush valve 50, and flush valve 50 is arranged to discharge water for flushing purposes through the flush tube 52 to a fixture such as a water closet, a slop sink, or the like. As is well known, a direct-connected flush valve, such as flush valve 50, is arranged to open itself hydraulically upon a manipulation of handle 51, and to close off hydraulically after a predetermined quantity of water has been discharged. The function of the valve 1 is to close off the supply entirely when desired, so as to permit of inspection or repair of the flush valve 50, and also to quietly throttle the flow through the flush

valve 50 to some predetermined rate of flow, ordinarily from eighteen to thirty gallons a minute.

The control valve

Referring now to Figures 1 to 3, and first to Figure 1, the improved control valve includes a casing 1 which has inlet 2 threaded to receive a supply pipe, and an outlet 3 threaded and machined to form one portion of the usual ground-joint union. The discharge end of the casing is provided with an accurately machined throttle throat around the entrance to which there is provided an accurately machined seat with which the beveled surface of valve 15 is pressed into sealing engagement when the valve is in the closed-off position illustrated in Figure 1.

In its construction, the device includes the slotted regulating stem 5 which passes through stem-packing 6, compressed by packing nut 4. Stem 5 has an annularly enlarged inner end 7 which works against the illustrated shoulder in the bonnet 9 to resist any tendency for the stem 5 to slide outwardly. The annular portion 7 of stem 5 is normally held snugly against the retaining shoulder by an outward force exerted by the water pressure.

The female-threaded adjusting gland 10 is provided adjacent the inner end of stem 5. This gland is rotatably held in position by the annular enlargement 11 thereon, which is contained in the annular recess provided by the retaining gland 12.

The stem 13 of valve 15 is threaded for movement back and forth within the adjusting gland 10 to close and open the valve 15 as desired when stem 5 is rotated to turn the gland 10. Valve 15 and stem 13 are prevented from rotating, during and after adjustment, by the guide stem 14, which operates within the illustrated drilled hole in bonnet 9.

The throttle proper, 23-21, shown best in Figures 6 and 7, is removably held concentrically against the end of the neck portion 29, on the discharge end of valve 15, by retaining screw 18.

The annular cushion assembly 24, shown best in Figures 8 and 9, is held in the illustrated position in the annular recess formed between the illustrated shoulder within outlet 3 and the supply end of discharge nipple 28. Nipple 28 is removably held in sealing engagement with the outlet 3 by the coupling nut 27.

The throttle construction

Referring particularly to Figures 6 and 7, the throttle proper comprises the metal insert member 23, which may be termed a thick washer or a short cylinder. The flat lower surface merges with the cylindrical outer surface by a radius rather than meeting at a sharp corner, as this construction was found to give better results. The wire-gauze covering 21 may comprise one or two layers. Best results were obtained with an inner layer of thirty-mesh Monel gauze and an outer layer of eighty-mesh Monel gauze. The wire-mesh covering is preferably first die-formed in the shape of a cup, following which the metal insert 23, with the lead washer 22 therein, is placed within the cup, and the upper side portions of the die-formed cup are then turned over and pressed or stamped tightly down into the lead washer 22 to form a smooth top surface. The hole through the top and bottom of the covering 21 and through lead washer 22 may then be punched to the same size as the central

hole through the insert piece 23. The lead washer 22 lies within the receiving recess in the insert piece 23, and its function is to yield more or less when the stamping is performed, and to hold the covering material firmly imbedded therein.

In order to provide for the ready removal of the throttle 21 through the outlet 3 of the casing after the nipple 28 and the cushion assembly 24 have been removed, the retaining screw 18 is equipped with a pull-off washer 20, which has four inwardly projecting prongs projecting into the annular recess in screw 18, between the head thereof and the threaded portion. Preferably, the prongs of washer 20 are first bent outwardly and upwardly sufficiently to enable the washer to be dropped in place over the threaded portion of the screw 18, assembled with the throttle piece. Following this, the prongs of washer 20 are flattened down to the position illustrated. In the assembled position of the throttle proper, washer 20 lies in the recess 19 in the end of neck portion 29 as illustrated in Figure 1.

The cushion assembly

The cushion assembly 24 includes a number of superposed washers 25, preferably about eight or nine, contained within the container 33 and stamped from, for example, thirty-mesh Monel wire gauze. Container 33 may be conveniently produced by forming a comparatively deep cup of thin material and then punching out the bottom portion of the cup, which is then inverted to form the top portion of the container 33. A slight inwardly extending rim of about one sixtieth-inch in diameter is left around this top portion of the container to retain the washers 25 in place after they are finally assembled. The solid-metal support washer 26 is next inserted through the open end of the formed cup, following which the sides of the cup may be forced inwardly to hold the washer 26 within the container 33 and to give a definite height to the container sufficient to allow the required number of washers 25 to lie uncompressed, as it has been found that best results are obtained when the individual washers have some freedom of longitudinal movement.

After the container 33 has been formed with the support washer 26 therein, the previously stamped-out washers 25 may be inserted from the top, each of them springing inwardly slightly to pass within the slightly inwardly turned top rim of the container.

Operation

The operation of the disclosed control valve will now be described. For this purpose, it will be assumed that this device has been installed as shown in Figures 4 and 5, in the closed-off position in which it is illustrated in Figure 1, and that the supply pressure has been admitted through the supply piping and the supply nipple 48, Figure 4, to the inlet 2 of the device.

The stem 5 is now turned in a counter-clockwise direction to correspondingly turn the adjusting gland 10 through the transverse blade 8 on the lower end of stem 5 and the cooperating notch in gland 10. The turning of glands 10 causes the threaded stem 13 to be drawn into the gland 10 to draw the valve 15 away from its seated position, rotation of the valve 15 and stem 13 being prevented by the guide stem 14.

When valve 15 is raised slightly from its seated position, a discharge path is opened through the

valve along the comparatively small space between the throttle 23-21 and the surrounding throttle throat in the casing 1. The flow first occurring is ordinarily a comparatively explosive mixture of air and water which causes considerable agitation in the supply piping. This action is ordinarily sufficient to cause the flush valve 50 to open more or less by a compression of the air lying within the usual upper or control chamber thereof before this air has been expelled and replaced by the incoming water.

It is to be noted that, in the initial opening stage of the control valve, the throttle 23-21 lies considerably below the fixed valve seat and that there is an annular pocket above the throttle between the neck 29 and the surrounding throat into which foreign matter carried in by the rushing mixture of air and water may find temporary lodgment. It is to be noted, also, that the jet direction is such that any such foreign material (such as pipe scale, chips from pipe threading, and white lead or other pipe-joint material) impinges against the neck portion 29 and is thus not driven directly into the covering 21 of the throttle 23-21. This provision insures the throttle does not become coated with material driven into it by the high-velocity jets at the moment of the opening of the valve.

As the valve is opened more widely, upon a further turning of the outside stem 5, the flow through the control valve and through the associated flush valve 50 is sufficient to reclose the flush valve in the event that it was raised from its seat more or less by the initial flow through the control valve. Following this, no further flow takes place as the control valve is opened further.

For the purpose of cleaning out the supply piping and enabling any foreign matter lodged within the control valve to be washed on through the flush valve 50 and be discharged from the piping system, the control valve is first opened fully to the position illustrated in Figure 3, following which the flush valve 50 is actuated one or more times to permit a full and unthrottled flow to occur, and to enable all the trapped air to be removed from the supply piping.

After the piping has been thus cleaned out, the control valve is then adjusted to a position more or less as shown in Figure 2, depending upon the supply pressure and the rate of flow during a flushing operation of valve 50.

It is to be noted that the throttle throat in the casing within which throttle 21 operates comprises a tapered portion 30, about three-eighths inch long in the illustrated device and having an angle of taper of about three degrees on a side, which tapered portion is followed by a straight or cylindrical portion 31 which is about one-eighth inch in length in the illustrated embodiment. Therefore, the width of the annular crevice between throttle 21 and the surrounding throat may be increased or decreased as desired by adjusting the valve so that the throttle is extended a lesser or greater distance into the throat portion 30.

The passage of the stream through the annular throttling throat defined between the throttle 21 and the surrounding throat wall is considerably quieted by virtue of the character of the surface of the throttle 21. For the higher pressures, the annular jets discharged through the restricted throttling throat are still capable of giving rise to noise unless further acted upon or cushioned, as by the cushion element 24. The annular jets tend to penetrate the layers 25 more or less, and

they emerge radially inward into the free inner opening in the cushion element 24, and then flow through the support washer 26, and thence through the nipple 28, as a quiet slowly moving stream.

It has been found that the support washer 26 needs to have a thickness greater than that dictated by considerations of support strength, in order for the device as a whole to be satisfactorily quiet for the intended purpose. Although no altogether satisfactory explanation for it has been found, when the washer 26 is, for example, only about one thirty-second inch in thickness, some noise is still observed at the higher pressures and rates of flow, which noise is effectively eliminated by increasing the thickness of the washer 26 to about one-sixteenth inch or slightly greater. This thickness seems to be ample for the purpose, and no further improvement has been noted as the thickness is further increased over that illustrated, although no bad effects have been noted by any additional increase in thickness. Experiments were conducted to determine the effect of omitting washer 26 entirely, and it was discovered that the device is not nearly so efficient in quieting the flow without the support washer 26 in the assembly, even though it was not absolutely required for mechanical considerations.

Throttle and cushion removal

As will be observed, both the cushion assembly and the throttle assembly can be readily removed for inspection or renewal without closing off the main supply valve (not shown), as this may be done by closing off the illustrated control valve. With the valve thus closed off as shown in Figure 1, the flush valve 50 and nipple 28 can be disconnected and removed by unscrewing coupling nut 27.

The cushion 24 can now be readily removed through the outlet 3, following which screw 18 can be backed out to free throttle 23-21 and permit the throttle also to be removed through the outlet, with the valve 15 in seated position and the supply pressure on. In the event that the throttle 23-21 tends to stick in place, the enlarged threaded portion of screw 18 engages the inwardly turned prongs of pull-off washer 20, and thus forcibly pulls the throttle 23-21 away from the face of neck portion 29, and further brings the throttle out of the straight portion 31 of the throat to free it for ready removal.

When the throttle 23-21 is to be replaced, the throttle assembly, including screw 18, need only be inserted and then brought up tight with the screw 18. With the construction illustrated, no special attention need be paid to the problem of centralizing the throttle on the valve, for the clearance is small between the outside diameter of the covered throttle and the inside diameter of throat portion 31, and the valve 15, in closed position, is held accurately centralized by four short ribs 16, diametrically opposed in pairs, of which portions of two can be seen in Figures 2 and 3. The profile of ribs 16 is shown in dotted outline at 17 in Figure 1. The same centralizing feature may be conveniently employed for assembling the throttle initially.

Since the guides 16 are very short, the valve 15 raises free from them almost as soon as it is unseated, permitting freedom of lateral movement of valve 15 and throttle 21 sufficient to permit foreign particles as large as the total clearance between the throttle 21 and the sur-

rounding throat to pass through in the working position of adjustment.

Following the replacement of the throttle 23-21, the cushion assembly 24 may be replaced, and the flush valve 50 reconnected through nipple 28 and coupling nut 27. Then, as soon as the control valve is opened and is set for the desired rate of flow, the installation is ready for further operation.

Prevention of clicks and wear

With further reference to the regulating-stem arrangement, it may be pointed out that the outside stem 5 is normally pressed outwardly by the water pressure, whereas the valve 15 and valve stem 13 are forced in the opposite direction during each flushing operation of the valve 50 by the pressure drop through the control valve. During the development of this control valve, embodiments were tested wherein regulating gland 10 was made in one piece with adjustment stem 5, but this construction gave rise to a double click during each flushing operation, one click at the start and another at the finish. The click at the start of the flush was caused by a longitudinal down-stream movement of the valve assembly, the adjustment stem moving through the stem packing 6 by whatever amount of longitudinal play was allowed in the parts for manufacturing tolerance. The click at the end of the flush came as a result of a movement in the opposite direction to the allowed extent of longitudinal movement when the discharge pressure was built up during the closing movement of the flush valve. Besides being annoying by the emitted clicking sounds, these longitudinal movements of the adjusting mechanism of the valve resulted in considerable wear of the concerned parts, and particularly of the packing 6. Such wear of the packing would, in many cases, allow leakage around the stem. With the disclosed arrangement, in which the adjusting gland 10 is physically separated from the adjusting stem 5, although caused to rotate therewith, all such clicking and wearing actions have been effectively eliminated.

What is claimed is:

1. In combination, a valve casing having an inlet and an outlet interconnected through a discharge throat, a shut-off valve and adjustment means for bringing it into and out of seating engagement with said casing around the inlet side of said throat, a throttle secured to said valve on the discharge side thereof, said throttle being variably cooperative with said discharge throat as said valve is adjusted toward and away from its seated position, said throttle being disposed within said throat when the valve is in seated position and being sufficiently small that it is removable through said throat and the outlet of the valve casing, screw means for holding said throttle attached to said valve when turned in one direction, and pull-off means associated with said screw means and effective responsive to said screw means being turned in the opposite direction for pulling said throttle away from the valve and through said throat to facilitate ready removal of the throttle through the outlet of the casing.

2. A quieting or cushioning structure for use in throttling devices, comprising a number of washers cut or stamped from woven-wire gauze or screen material, a retaining member receiving and encircling the washers in superposed relationship to one another, said member having the

opposed ends thereof turned inwardly to provide internal-retaining flanges, and an imperforate washer located adjacent the first-named washers within said retaining member on the downstream side of the first-named washers to support them against distortion responsive to the impact of high-velocity jets.

3. A quieting or cushioning structure for use in throttle valves, comprising a number of washers cut or stamped from porous material, a retaining member receiving and encircling the washers in superposed relationship to one another, said member being provided with opposed flanges to hold the washers therein, and a further washer of comparatively rigid and imperforate material assembled adjacent the first-named washers, said last-named washer being of approximately the same internal diameter as the first-named washers and having a thickness immediately surrounding the opening therethrough greater than one thirty-second inch, whereby the quieting efficiency of the assembly is improved.

4. A quieting or cushioning structure for use in throttle valves, comprising a number of washers cut or stamped from porous material, a retaining member receiving and encircling the washers in superposed relationship to one another, said member being provided with opposed flanges to hold the washers therein, and a further washer of comparatively rigid and imperforate material assembled adjacent the first-named washers, said last-named washer being of approximately the same internal diameter as the first-named washers and having a thickness immediately surrounding the opening therethrough greater than one twenty-fourth of the diameter of the common passageway through all said washers.

5. A quiet-flow throttle and valve comprising a casing having an inlet and an outlet interconnected by a passageway, said casing being of generally tubular or vase-like configuration and having its inlet located at one side thereof and the outlet located at an end, a valve located within said casing and controlled by manual-adjustment means operating through the end of said casing opposite the outlet, said valve means being closable in the direction of flow through the casing against a seat in the casing axially aligned with the outlet, a forwardly projecting throttle mounted on said valve and projecting in the direction of the outlet when the valve is in closed position, said throttle including a solid disc member having a covering of porous metal thereon, an annular washer-like cushion assembly located in said casing downstreamwardly of the seated valve and of the throttle, and means facilitating the removal and replacement of said cushion assembly and said throttle through the outlet of the casing while said valve is closed off to prevent the concurrent outflow of fluid.

6. A throttle structure for use in an adjustable throttle device, said structure comprising a body member having the general shape of a disc or short cylinder, a thin disc of soft metal recessed into one flat face of said body disc, and a covering of drawn porous sheet metal fitting over the other flat face of said body member and over the cylindrical outer surface, and folded down over the flat face containing the thin soft-metal disc, and imbedded in the said soft-metal disc by pressure to retain the cover in place.
